DAMPING MEANS FOR RAILWAY TRUCKS

James C. Settles and Claude L. Orr, Columbus,
Ohio, assignors to The Buckeye Steel Castings
Company, Columbus, Ohio

Application October 15, 1945, Serial No. 622,434

10 Claims. (Cl. 105—197)

1

This invention relates to improvements in railway trucks, and more particularly to means for holding the friction wedges or shoes of damping means in the wedge pockets of a bolster (in opposition to the pressure of the wedge springs) while the bolster is being applied to, or removed from, the side frame.

The primary object of the invention is to improve the damping means retaining structure disclosed in our application, Serial No. 592,678, dated May 8, 1945.

In general, the improvement consists in providing for the use of two retaining pins to hold each friction wedge or shoe in a pocket of the bolster, against the pressure of the wedge spring, while the bolster is being introduced into, or removed from, the side frame. In our earlier application, a single retaining pin is used near the bottom of the friction wedge. It is important that the overall width across the two friction wedges be less, with the retaining pins applied, than the width between the side frame columns, in order to permit easy application or removal of the bolster end, in the side frame bolster opening. Our improved construction in which two retaining pins are used with each shoe or wedge, satisfactorily retains the wedges within the desired limits with allowance for the usual manufacturing tolerances because there will be no tendency of either wedge to pivot about a single retaining pin.

Additional objects, advantages and features of the invention reside in the construction, arrangement and combination of parts involved in the embodiment of the invention, as will be apparent or understood from the following description and accompanying drawings, wherein:

Fig. 1 is a side elevation, partly in longitudinal vertical section, of the medial portion of the side frame of a railway car truck with our improvements incorporated in such truck.

Fig. 2 is a transverse horizontal sectional view taken on the line 2—2 of Fig. 1.

Fig. 3 is a transverse vertical sectional view taken on the line 3—3 of Fig. 1.

Fig. 4 is a transverse vertical sectional view of an end portion of the bolster, forming part of the present invention, taken on the line 4—4 of Fig. 5.

Fig. 5 is a top plan view of such end portion of the bolster.

Fig. 6 is a fragmentary sectional view similar to the upper left portion of Fig. 1 with the wedge actuating spring removed.

Referring to the drawings, 6 designates a truss-type side frame of a railway truck provided with

2

spaced bolster guide columns 7 arranged at opposite sides of a bolster opening 8. The spring seat 9 of each side frame supports truck springs 10 positioned within the bolster opening. A bolster end or arm 11 extends into the bolster opening, rests on the springs and is guided by the columns 7. At each side of the bolster arm or end, a pocket 12 is formed for the reception of a friction wedge or shoe 13 and each of the wedges has its reduced end at the top thereof. Each wedge also has a vertical face 14 to frictionally engage a vertical wear plate 15, fixed to the guide column. The wedge also has an inclined upper face 16 slidably engaging a complementary inclined face 17 formed by the bolster and arranged in the pocket. As may be seen from Fig. 1, the inclined surfaces 16 and 17 converge downwardly, and each of the surfaces 16 is slightly convex, as indicated at 18 in Fig. 6, to allow the friction wedge to rock relatively to the bolster and to permit the bolster to rock relatively to the side frame.

The bottoms of the bolster pockets are provided with inclined surfaces 19, which are substantially perpendicular, respectively, to the inclined surfaces 17 and converge upwardly to serve as supports for the bases of springs 20, preferably of coil type. The upper ends of the springs bear against sloping surfaces 21 in the tops of the wedges, parallel to the surfaces 19. With this arrangement, it is obvious that the springs 20 diverge upwardly and are substantially parallel to the inclined surfaces 16, 17 of the wedges and bolster.

Holes 22 and 23 are provided in the friction wedges and bolster, respectively, on the axes of the wedge springs 20 for insertion of bolts (not shown) by means of which the springs 20 are compressed so that upper and lower retaining pins can be inserted in the then aligned upper and lower friction wedge and bolster holes 24 and 25, and 26 and 27, respectively. After the retaining pins (not shown) are in place, the bolts, which were passed through holes 22 and 23, are removed and the bolster is then applied to the side frame, by introducing the bolster end into the lower portion of the bolster opening and then raising the bolster to bring the vertical surfaces 14 of the friction shoes into confronting relation with the wear plates 15 of the columns 7. Then the retaining pins are removed from the holes 24, 25, 26 and 27, so that the force of the springs 20 is exerted against the side frame columns, in order to produce the desired damping action.

Each of the wedge shoes 13 is provided at its top with a recess 13a to permit the introduction of a wrench or the like in releasing a bolt, passed through the holes 22 and 23, used to hold the spring 20 in compressed condition.

To permit easy withdrawal of the pins from the lower holes 26, 27, the spring pressure against these pins can be released by prying with a bar between the tops 28 of the friction wedges and the underside of the top member 29 of the side frame, or small blocks (not shown) can be placed on top of the friction wedges and the bolster jacked upward so that the blocks bear against the part 29 of the side frame. The wedge spring pressure on the pins passing through holes 24 and 25 can be released by prying sideways between the side frame columns and substantially vertical abutment faces 30, provided for this purpose, on lugs 31, provided at the top of the friction wedges.

The same procedure as described above for releasing spring pressure on the retaining pins may be used to compress the wedge springs 20 and align the holes 24 to 27 to permit the insertion of the retaining pins when the bolster is to be removed from the side frame. Fig. 1 shows the position of the friction wedges with the bolster applied to the side frame and the retaining pins removed. It should be evident, however, from the above description that compression of wedge springs 20, as described, will align the holes 24, 25 and 26, 27 to permit application of the retaining pins.

It will be noted that each wedge shoe has a single upstanding lug 31 arranged between a pair of upwardly projecting lugs 31a on the bolster, and in accordance with the invention, the holes 24 are in the lugs of the wedge shoes and the holes 25 in the lugs of the bolster. As best shown in Fig. 3, the top member 29 of the side frame is of inverted channel section and of sufficient width to permit the lugs 31 and 31a to pass between the vertical flanges 32 and 33 of the channel when the bolster is raised to the top of the bolster opening, in order to apply or remove the bolster supporting springs 10.

While we have disclosed the invention in a practical embodiment, it will be understood that this is exemplary and that changes of construction and proportions of parts and equivalents, mechanical or otherwise, may be made therein without departing from the spirit of the invention, except as may be more specifically indicated in the appended claims.

What we claim and desire to secure by Letters Patent is:

1. In a railway car truck, a side frame member provided with bolster guide columns arranged at opposite sides of a bolster opening, a bolster portion extending into said opening and having diverging surfaces, spring means supporting said bolster portion from the side frame, friction wedges arranged at opposite sides of the bolster portion and frictionally engaging said columns and said diverging surfaces, spring means positioned in the bolster portion substantially parallel to said diverging surfaces and yieldingly urging the wedges against said columns, bolster lugs provided with horizontal apertures, and other lugs projecting upwardly from the wedges and having horizontal apertures adapted to be brought into alignment with the apertures of the bolster portion to receive retaining pins for holding the last-mentioned spring means in compressed condition, one of the lugs of one of the wedges hav-

ing a substantially vertical abutment surface confronting one of the bolster guide columns.

2. In a railway car truck, a side frame member provided with bolster guide columns arranged at opposite sides of a bolster opening, a bolster portion extending into said opening and having diverging surfaces, spring means supporting said bolster portion from the side frame, friction wedges arranged at opposite sides of the bolster portion and frictionally engaging said columns and said diverging surfaces, spring means positioned in the bolster portion substantially parallel to said diverging surfaces and yieldingly urging the wedges against said columns, said side frame member having a top portion of inverted channel shape, lugs arranged at the top of the bolster portion and provided with horizontal apertures, and lugs projecting from the tops of the wedges into said channel and provided with horizontal apertures adapted to be brought into alignment with the apertures of the bolster portion to permit retaining pins to be inserted into the holes for holding the last-mentioned spring means in compressed condition.

3. In a railway car truck, a side frame member provided with bolster guide columns arranged at opposite sides of a bolster opening, a bolster portion extending into said opening and having diverging surfaces, spring means supporting said bolster portion from the side frame, friction wedges arranged at opposite sides of the bolster portion and frictionally engaging said columns and said diverging surfaces, spring means positioned in the bolster portion substantially parallel to said diverging surfaces and yieldingly urging the wedges against said columns, said side frame member having a top portion of inverted channel shape, lugs arranged at the top of the bolster portion and provided with horizontal apertures, said lugs being movable into said channel, and lugs projecting from the tops of the wedges into said channel and provided with horizontal apertures adapted to be brought into alignment with the apertures of the bolster portion to permit retaining pins to be inserted into the apertures for holding the last-mentioned spring means in compressed condition.

4. A friction shoe for damping a railway truck comprising a unitary member having a vertical guide surface at one side thereof and a sloping surface at the opposite side thereof, said member having a top provided with an aperture, the walls of which are substantially parallel with said sloping surface, the underside of said top having a spring contact surface arranged substantially perpendicular to the walls of the aperture, the top of the member having a recess communicating with the aperture, and a lug projecting upwardly from the top of the member and provided with a horizontal rod receiving aperture.

5. In a railway car truck, a column member, a bolster member resiliently supported for movement along the column member, said bolster member having a pocket therein open towards the column member, a friction shoe in said pocket, cooperating inclined surfaces on the shoe and on the bolster member within the pocket, a spring compressed between the bolster member and the shoe substantially parallel to said inclined surfaces urging the inclined surface on the shoe into contact with the inclined surface on the bolster to thereby urge the shoe towards the guide column, spaced lugs on the bolster member, a lug on the shoe extending between said spaced lugs, all of said lugs having pin receiving

apertures therein arranged laterally of said spring, and said shoe and bolster having pin receiving apertures therein arranged at the other side of the spring.

6. In a railway car truck, a bolster member, said bolster member having a pocket therein open at one side of the bolster, a shoe in said pocket, cooperating inclined surfaces on the shoe and the bolster member, a spring between the bolster member and the shoe applying force to the shoe in alignment with said inclined surfaces and moving the inclined surface on the shoe into engagement with the inclined surface on the bolster member to urge the shoe out of said pocket, said bolster member and said shoe having pin receiving apertures arranged at one side of the spring, and said shoe and said bolster having pin receiving apertures therein arranged at the other side of said spring.

7. In a railway car truck, a bolster member, said bolster member having a pocket therein open at one side of the bolster member, a shoe in said pocket, cooperating inclined surfaces on the shoe and on the bolster member, a helical spring open along the axis thereof compressed between the bolster member and the shoe arranged generally parallel with respect to said inclined surfaces for urging the inclined surfaces into contact and thereby urging the shoe out of said pocket, said shoe and said bolster member each having a hole therein both aligned with the axis of the helical spring, said shoe and bolster member having pin receiving apertures therein at one side of said spring, and said shoe and said bolster having pin receiving apertures therein at the other side of the spring.

8. A friction shoe for the damping mechanism of a railway car truck comprising, a rigid member having a relatively flat front face, a sloping surface at the opposite side of said member, a top wall for the shoe arranged substantially at right angles to said sloping surface, said top wall having an aperture therethrough with the axis

of the aperture substantially parallel to said sloping surface, a spring seat under said top wall around said aperture substantially at right angles to said sloping surface, and a lug carried by the top of said shoe having an aperture therethrough.

9. A friction shoe for snubbing movement of a member of a railway car truck comprising, a member having a relatively flat face at one side thereof, a sloping surface at the opposite side of said member, a top wall for the shoe arranged substantially at right angles to said sloping surface, said top wall having an aperture therethrough with the axis of the aperture substantially parallel to said sloping surface, a lug carried by the top of said shoe having an aperture therethrough, and the front edge of said lug being substantially parallel to said flat face.

10. In a bolster member for a railway car truck, said bolster member having a pocket therein open towards one side thereof, an inclined surface on the bolster member within the pocket, a spring seat within said pocket at right angles to said inclined surface, said bolster member having a hole therethrough with the axis thereof at right angles to the spring seat, spaced lugs carried by and extending upwardly from the top of the bolster member, and said lugs having aligned holes transversely therethrough.
